UNITED STATES PATENT OFFICE.

WILLIAM HART, OF SOUTH BARRE, MASSACHUSETTS.

ATTACHMENT FOR WORSTED TOP FINISHERS.

Application filed October 28, 1921. Serial No. 511,214.

To all whom it may concern:

Be it known that I, WILLIAM HART, a citizen of the United States, residing at South Barre, in the county of Worcester and State of Massachusetts, have invented new and useful Attachments for Worsted Top Finishers, of which the following is a specification.

This invention relates to a device for use 10 in balling the sliver on a worsted top finisher.

The principal objects of the invention are to make an exceptionally good looking top for the market and also to provide improved 15 means for putting a uniform false twist into the sliver so that the ball will be compact and loose strands will not be left on the top in unwinding in the drawing room, thus avoiding one of the principal causes of the constant 20 breaking of the sliver; also to provide a construction in which entanglements are avoided when unwinding in the drawing operation; and to provide an easy running and positive driving mechanism for operating 25 the same.

Further objects and advantages of the invention will appear hereinafter.

Reference is to be had to the accompanying drawings, in which

30 Fig. 1 is a front view of an attachment constructed in accordance with this invention for use on a top finisher;

Fig. 2 is a plan of the same, and

Fig. 3 is a sectional view through the center of one of the funnels.

As is well understood in the wool finishing art, the sliver after it comes from the comb is taken to a box in the form of a can where it is gilled and conditioned. Then it is taken 40 from this box to the worsted top finisher where the last operation in the combing department is performed. On the top finisher there is a balling head by means of which the sliver is wound into balls.

45 This invention is designed to be applied to the top finisher and to control the sliver as it passes from it to the balling head.

One of the functions which it performs is to provide a false twist, that is, first a twist 50 in one direction and then in the other, in the sliver so that the same is kept taut and yet there is no real twist put into the sliver that will affect it when it is unwound, the two twists neutralizing each other. The balling head on the finisher which travels back and

forth furnishes all the power for the attachment.

The traveling balling head plate 10 reciprocates back and forth in the ordinary machine. The means for operating it I have 60 not illustrated here as it does not constitute a part of this invention. It is provided with a bolt 11 or other fastening device which has secured to it a frame 12. The opposite ends of a chain 13 are secured to this frame to 65 provide what is in reality an endless chain. This passes over an idler sprocket wheel 14 on a shaft 15 and a power transmitting sprocket wheel 16 on a parallel shaft 17. The reciprocation of the plate 10 will oscillate these shafts 15 and 17 and cause each of them to turn several revolutions one way and then a corresponding number of revolutions in the other way. As the drive is positive and there is no slippage there is no lost motion in starting or stopping and no danger of providing more rotation in one direction than in the other.

The shaft 17 is provided with a sprocket wheel 18 larger than the wheel 16. Over the 80 larger wheel passes an endless sprocket chain 19 which meshes with two sprocket wheels 20, each mounted on a rotatably mounted funnel 21. These funnels are mounted in bearings 22 on the frame 23 as 85 is usual except that they are provided with ball bearings to reduce the friction. Each funnel is constructed in the usual way having an enlarged inlet for guiding the strands of the sliver into it. The butt is provided 90 with an opening 25 therethrough for discharging the sliver, this opening being arranged diametrically and having flat opposite sides but intended at the center to form a shape similar to a figure 8 and remove dead 95 space or non-revolving area as much as possible. This guides the sliver out to the rolls 26 on which the ball 27 is formed in the usual way.

It will be seen that any movement given 100 to the sprocket wheel 16 is multiplied by the connections to the sprocket wheels 20 and funnels 21, but the motion is always positive as stated above and the twist in both directions is always the same. This provides 105 a positive multiple false twist and improves the appearance and condition of the final product, that is, the ball.

The sliver is kept taut by the fact that the amount of twist is greater than usual and 110

there is not much chance of a few strands being left on the top in unwinding in the drawing room. Therefore, the breakage is materially reduced. It produces a well made 5 solid top holding its shape under rough usage and free from entanglements in unwinding.

It is to be observed that the so-called oscillation does not consist in a mere turning 10 motion through a small arc but, where it affects the sliver, that is at the funnel, it consists of a rotation of the funnel through a plurality of complete revolutions in each direction. This need not be a plurality of 15 exactly complete revolutions but it is more than one complete revolution and it may involve several complete ones and a part of one in addition. This would be according to the proportions of the gearing. But at any 20 rate the rotation in each direction is equal and, being positively driven, there is no way that, on account of slippage or the slowing up of the motion at the end of the stroke of the balling head plate, there can be any inequality in the twist. Therefore, when unwound from the ball all the twists will exactly neutralize each other. On account of 25 having more than a complete rotation in each direction also the sliver is laid on the ball in a more even and compact manner than has been possible with the mechanisms heretofore known.

Although I have illustrated and described only a single form of the invention I am 30 aware of the fact that modifications can be made therein by any person skilled in the art without departing from the scope of the invention as expressed in the claims. Therefore, I do not wish to be limited to all the 35 details of construction herein shown and described but what I do claim is:—

1. The combination of a worsted top finisher having a balling head plate reciprocably mounted thereon, with a funnel and 40 positive means for transmitting the reciprocating motion of said plate to the funnel at all times to rotate it a plurality of revolutions in one direction when the plate moves forward and a plurality of revolutions of exactly equal amount in the other 45 direction when the plate moves back.

2. The combination of a worsted top finisher having a balling head plate reciprocably mounted thereon, with a pair of funnels located parallel with each other, and positive means for transmitting the reciprocating motion of said plate to the two funnels at all times to rotate each of them a plurality of revolutions in one direction forward and a plurality of revolutions of exactly equal amount in the other direction when the plate moves back.

3. In a worsted top finisher, the combina-

tion with the reciprocating balling head plate, of an endless chain movable therewith, 65 a sprocket wheel over which said chain passes adapted to be oscillated by the operation of the chain and plate, a pair of funnels for the sliver located parallel with each other, and means for transmitting the oscillating motion of said sprocket wheel to both of said funnels to oscillate them simultaneously at a higher speed than that of the chain.

4. In a worsted top finisher, the combination with the reciprocating balling head plate, of an endless chain secured thereto and movable therewith, a pair of sprocket wheels over which said chain passes, whereby they will be oscillated by the operation 80 of the chain and plate, a pair of funnels for the sliver located parallel with each other, and means for transmitting the oscillating motion of one of said sprocket wheels to both of said funnels to oscillate them simultaneously, and for multiplying the motion to cause the funnels to rotate a plurality of revolutions at each oscillation of the first named sprocket wheels.

5. In a worsted top finisher, the combination with the reciprocating balling head plate, of an endless chain movable therewith, a pair of sprocket wheels over which said chain passes adapted to be oscillated by the operation of the chain and plate, a pair of 95 funnels for the sliver located parallel with each other, a shaft on which one of said sprocket wheels is mounted, a sprocket wheel of larger diameter on said shaft, a pair of sprocket wheels on the funnels of smaller 100 diameter than the large wheel, and a second endless chain passing over the last three wheels.

6. The combination with a reciprocatory balling head plate of a worsted top finisher, 105 of a shaft, means connected with said top plate for oscillating said shaft as the plate reciprocates, a sprocket wheel on said shaft, a pair of funnels each having a sprocket wheel thereon of smaller diameter than the 110 first named sprocket wheel, and an endless chain connecting the three sprocket wheels to rotate the funnels a plurality of revolutions whenever the shaft is rotated one revolution.

7. In a balling head for a top finisher, the combination of a funnel and means connected with the finisher for oscillating it positively a plurality of revolutions in each direction, with a guide in the funnel having 120 a passage located diametrically and contracted at the center on opposite sides for the purpose described.

In testimony whereof I have hereunto affixed my signature.

WILLIAM HART.
